SWITCH

George H. Berkholder, Minneapolis, Minn., assignor to Minneapolis-Honeywell Regulator Company, Minneapolis, Minn., a corporation of Delaware

Application January 5, 1946, Serial No. 639,334

6 Claims. (Cl. 200—67)

1

My invention relates to an improvement in snap switches of the magnetic type, and means by which an actuating force is applied to effect snap action of the contacts; and particularly relates to snap switches of the sensitive type adapted to be actuated by means moved gradually in response to change in a condition, such as temperature or pressure.

An object of this invention is to provide a switch of the character described which is capable of handling relatively heavy loads.

A more specific object is to provide, in a switch of the class described, a novel arrangement of parts whereby the contacts upon initial engagement are firmly held in that condition and vibration between them is substantially eliminated.

A further object of this invention is to provide a switch blade having a relatively small amplitude of movement which dampens or otherwise reduces bouncing between the contacts of a snap switch.

A still further object is to provide a switch blade with an internal bias which force aids in substantially eliminating bounce of the contacts of the snap switch.

Another object is to provide a new and improved switch in which bouncing or relative vibratory action between the contacts following initial closing of the switch is minimized to aid in avoiding fusing of the contacts.

It is yet another object of my invention to provide a snap switch with fewer parts than the devices of the prior art and at the same time accomplish better results in the present snap switch than the results which have heretofore been obtained.

Other and further objects and advantages of my invention will be found in the description, the drawing, and the appended claims.

For a complete understanding of the invention, reference may be had to the following detailed description and accompanying drawing, wherein:

Figure 1 is a sectional view in elevation of the improved snap switch;

Figure 2 is a top plan of the snap switch, the cover removed;

Figure 3 is a detailed view showing the improved switch blades employed in the snap switch.

Figure 4 shows the switch blade in unstressed condition.

The snap switch 10 is shown mounted in a casing 11 which comprises a base portion 12 and a removable cover portion 14. The removable cover portion 14 has an aperture 16 receiving a

2

reciprocating button 18 having an enlarged head portion 20 spaced inside the casing 11.

A U-shaped bracket 22 is secured by a screw 24 to a terminal 26 in the base 12 of the switch 10 housing 11. A pivoted contact carrying arm is provided in the form of an armature 28 having a cut-out portion 30 in its outer end to accommodate a contact. The armature 28 is formed with upturned flanges 32-32 on its opposed sides adjacent its inner end. The armature 28 is also provided with a substantially right angular extension 33 at its inner end and having a substantially horizontal flange portion 34 extending from the right angular extension 32. A pin 36 extends through apertures in the arms of the U-shaped bracket 22 and the pin 36 also extends through apertures in the upstanding lugs 32-32 of the armature 28 for pivotally mounting the armature 28 on the pin 36. A resilient arm 38 is secured by appropriate means to the flange 34 of the armature 28 which is provided with a raised portion 40 for cooperating with the reciprocating button 18. A contact 29 is secured to the armature 28. There is an electrical conductor 42 connecting the armature 28 with the terminal 26. A biasing spring 44 is connected in an aperture in flange 34 of the armature 28 and its outer end is secured to anchoring means in the base of the housing 11.

There is a terminal 46 mounted in the base 12 of the housing 11 which has an integral flat portion 48 extending inside the switch housing 11. A contact 50 is mounted in the flat portion 48 of the terminal 46. A permanent magnet 47 is mounted adjacent the contact 50. A second contact 52 mounted in the flat portion 48 of the terminal 46 is adapted to engage the contact 29 on the armature 28. The contact 52 is provided with a shank portion 55 which is externally threaded for cooperating with screw threads in an aperture in the terminal 46. Contact 52 may be adjusted to determine the spacing between the armature 28 and the magnet 47 when the contacts are closed and so provide the desired operating differential of the switch. A screw 54 is adapted for maintaining the adjustable contact 52 in its adjusted positions.

A switch blade 56 of resilient spring metal is secured to a raised portion of the armature 28 at 58. The blade is shown in unstressed condition in Figure 4. When assembled in the switch the resilient spring metal blade 56 has a flat portion 60 at its inner end and an angular portion 62 extending from the flat portion 60 to a point 64 on the switch blade 56. The switch blade 56

also has a portion 68 that is normally flat as seen in Figure 4 but assumes a concave form when assembled in the switch which extends longitudinally of the blade from the point 64 adjacent its inner end to a point 68 adjacent its outer end. The switch blade 56 is provided with the angular portion 68 which extends downwardly from the point 68 and merges into a flat portion 70 at the outer end of the switch blade. A movable contact 72 is fastened to the flat portion 70 of the blade 56 and is receivable in the cut-out portion 30 of the armature 28. The contact 72 engages the stationary contact 50 prior to engagement of the contacts 29 and 52 and the portion 70 of the blade 56 is pressed back from the armature 28 in the switch closed position to provide a predetermined minimum contact pressure.

The concave longitudinal portion 68 of the switch blade 56 engages the armature 28 at substantially a point 76 forming a fulcrum thereon, for the blade 56. The rear portion of the blade 56 is formed with an internal bias and the internal bias in the switch blade 56 exerts a downwardly component force on the armature 28 at the fulcrum point 76. There is also a preformed internal bias in the angular portion 68 of the switch blade 56 and the component force of the bias is exerted downwardly at the contact 72.

The biasing spring 44 holds the armature 28 and the switch blade 56 in the position shown in Figure 1 when no force or insufficient force is applied to the armature 28 through the resilient arm 38 and the plunger 18 by an external force and thereby the movable contacts 29 and 72 are maintained out of engagement with the contacts 52 and 50, respectively. There is a Bakelite stop member 78 carried by a bracket 80 which is appropriately secured to the base portion 12 and the stop member 78 limits the upward movement of the switch blade 56 and armature 28.

If the button 18 is gradually depressed, energy will be stored in the resilient arm 38, but the armature 28 will remain in its upper position until the moment applied thereto by arm 38 overcomes the opposing moment due to the spring 44, at which time the armature will start to move downwardly. As the armature starts to move downwardly it is increasingly attracted by the field of the magnet 47 and is pulled downwardly with a snap action and the contact 72 engages contact 50 with a snap action. After contact 72 engages contact 50, then contact 29 carried by the armature 28 engages the contact 52. The contact 72 tends to bounce when it engages contact 50 and sets up vibration in the switch blade 56. The armature 28 will also bounce on engagement of contacts 29-52 but these contacts are not relied on to make or break the circuit. In order to prevent rapid deterioration of the contacts it is essential that vibration of the blade 56 and the contact 72 be of extremely short duration. In order to stop the vibration the energy causing the vibration must be dissipated. The front portion of the blade 56 or the portion from the fulcrum point 76 to the outer end thereof vibrates when the contact 72 engages the contact 50, and the fulcrum point 76 tends to move slightly towards the secured end of the switch blade 56 as the portion 70 is pressed back from the armature 28. As the blade 56 vibrates the fulcrum point 76 between the blade 56 and the armature 28 shifts back and forth along the length of the armature. Part of the shifting of this point is due to a rocking effect and part of the shifting is frictional sliding. The sliding that takes place

between the blade and the armature dissipates a large part of the vibrating energy. Also the effective spring rate of the outer portion of the blade changes with the shifting of the point 76 and this action appears to aid in stopping the vibration.

It will be noted that the blade 56 is in engagement with the armature 28 at the point 76 when the switch is open as seen in Figure 1. When the contacts are closed and the portion 70 of blade 56 is pressed back from the armature the blade will still engage the armature intermediate its ends but the point 76 will have shifted slightly away from the contacts. Since the normal shape of the blade 56 is as shown in Figure 4, its assembly on the armature 28 as shown in Figure 1 results in sufficient downward bias at the point 76 to maintain that portion of the blade firmly in engagement with the armature in all operative conditions of the switch. Hence, the sliding action that occurs at this point between the blade and armature as the contact 72 moves with respect to the armature absorbs energy. Vibratory energy of the contact 72 due to impact with the contact 50 is quickly dissipated in friction and arcing between these contacts is thus greatly reduced, increasing the life of the switch and increasing its capacity.

When the external force which is applied to the armature through the plunger 18 and resilient arm 38 decreases due to a change in the condition, the armature 28 will remain in its lower position as determined by engagement of the movable contact 29 engaging stationary contact 52 due to the force of the magnet, but as the force further decreases on the armature 28 the force of the spring 44 will be sufficient that the magnetic force is finally overcome and the armature 28 moves suddenly (due to the non-linear change of the magnetic force) to its open position, moving the contact 72 away from the contact 50 with a snap action.

It will thus be apparent that simple and efficient means are provided for substantially eliminating bounce of a contact associated with the switch blade of a snap switch.

While I have herein shown and described a specific embodiment of my invention, I wish it to be understood that modifications may be made without departing from the spirit of the invention, and that I intend therefore to be limited only by the scope of the appended claims.

I claim as my invention:

1. In a snap switch, in combination, a stationary contact, a movable contact arm, a spring blade carrying a movable contact on said arm for engaging said stationary contact, means for moving said movable contact into engagement with said stationary contact with a snap action, and means independent of said contacts for stopping said arm on movement in a contact closing direction, said spring blade being secured to said arm at one point and formed to bias the remote end thereof into engagement with said arm adjacent said movable contact, and slidably engaging said arm at a third point intermediate the first and second points.

2. In a snap switch, in combination, a stationary contact, a movable contact arm, a spring blade carrying a movable contact on said arm for engaging said stationary contact, means for moving said movable contact into engagement with said stationary contact with a snap action, and means independent of said contacts for stopping said arm on movement in a contact closing

direction, said spring blade being secured to said arm at one point and formed to bias the remote end thereof into engagement with said arm adjacent said movable contact, and otherwise engaging said arm only at a third point intermediate the first and second points, said blade being shaped to cause movement of said third point along said arm as the remote end of said blade is moved with respect to said arm.

3. In a snap switch, in combination, a first stationary contact, a movable contact arm, a spring blade carrying a first movable contact on said arm for engaging said first stationary contact, means for moving said first movable contact into engagement with said first stationary contact with a snap action, a second movable contact fixed to said arm cooperating with a second stationary contact for stopping said arm on movement in a contact closing direction, said spring blade being secured to said arm at one point and formed to bias the remote end thereof into engagement with said arm adjacent said movable contact, and slidably engaging said arm at a third point intermediate the first and second points.

4. In a snap switch, in combination, a stationary contact, a movable contact arm including an armature, a spring blade carrying a movable contact on said arm for engaging said stationary contact, a permanent magnet for moving said movable contact into engagement with said stationary contact with a snap action, and means independent of said contacts for stopping said arm on movement in a contact closing direction, said spring blade being secured to said arm at one point and formed to bias the remote end thereof into engagement with said arm adjacent said movable contact, and slidably engaging said arm at a third point intermediate the first and second points.

5. In a snap switch, in combination, a station-

ary contact, a movable contact arm, a spring blade carrying a movable contact on said arm for engaging said stationary contact, means for moving said movable contact into engagement with said stationary contact with a snap action, said spring blade being secured to said arm at one point and formed to bias the remote end thereof into engagement with said arm adjacent said movable contact, and otherwise engaging said arm only at a third point intermediate the first and second points, said blade having a bowed portion intermediate the point at which it is secured to said arm and its intermediate point of contact with said arm.

15 6. In a snap switch, in combination, a stationary contact, a movable contact arm, a spring blade carrying a movable contact on said arm for engaging said stationary contact, means for moving said movable contact into engagement with said stationary contact with a snap action, said spring blade being secured to said arm at one point and formed to bias the remote end thereof into engagement with said arm adjacent said movable contact, and frictionally engaging said arm at a third point intermediate the first and second points.
